UNITED STATES PATENT OFFICE.

CHARLES SCHULTZ JASSEY, OF EDGEWATER, NEW JERSEY.

EXPRESSION-MARKINGS FOR PLAYER-PIANO MUSIC-ROLLS.

1,140,746.

Specification of Letters Patent.

Patented May 25, 1915.

Application filed May 23, 1911. Serial No. 628,915.

To all whom it may concern:

Be it known that I, CHARLES SCHULTZ JASSEY, a citizen of the United States, residing in Edgewater, in the county of Bergen and State of New Jersey, have invented 5 certain new and useful Improvements in Expression-Markings for Player-Piano Music-Rolls, of which the following is a specification.

My present invention relates to an improvement in the manner of indication expression for the control on music rolls for player pianos or the like and consists of a series of indices or characters with or without exponents, said indices being placed on the roll in a continuous row, and while I prefer to place them in a straight row, one under the other, and preferably on the right hand side of said rolls near the edge thereof for convenience in translating, they may be placed so as to form a sinuous or zig-zag line throughout the length of the roll for the purpose of indicating tonal changes as well.

The manually operated mechanical means by which I translate the tempo indices forms the subject matter of a concurrently pending application.

Under the present standards of expression markings, as used by music roll manufacturers, the general control of the various passages throughout the music is only generally indicated, and the amount or degree control of the phases is left to the individual operator. While this arrangement permits the operator to instill his or her idea of expression into the music, as regards tempo, it has the disadvantage that should it be desired to reproduce the music as originally composed or arranged, under the present standard markings this could not be done as there is no class of indices with means to be operated therewith that will enable the composer to indicate, and the player to interpret, the finer degrees of shading that are the important factors in music.

While any operator might be able to interpret in a general way any of the so called popular pieces of music, the necessary finesse to properly interpret the heavier classical productions would require a broader general knowledge and more accurate and constant individual control of each phrase of the music in order to bring out the intent of the composer, and it is primarily for this purpose that my inven-

tion is intended. It is not necessary for the operator to follow the regular markings but if it is desired he or she may interpret the piece to suit themselves, but by my present improvement the music can always be produced as was originally intended.

A further improvement in my device is the application of an index at the beginning of the roll, this index consisting of a series 65 of indices of the same group as those used throughout that particular roll, and arranged transversely of the sheet. On placing this roll in the player and properly attaching it for operation, the operator is 70 enabled at a glance to see the group of tempo characters that will be used throughout the piece, and become familiarized with the same. It is intended that this shall be a reference for the convenience of the player 75 or operator to enable him before commencing to play, to locate the general zone on the expression dial under which the piece will be manually controlled, and which also may be used in conjunction with the usual 80 tempo markings, such as allegro, andante, or presto.

In the accompanying drawings the music roll 1 is shown in fragmentary form throughout.

Figures 1, 2, 3, and 4, show several variations of characters or indices. Fig. 5 shows a diagrammatic view of the music roll, tracker bar, and the indicator dial.

In Fig. 1 is shown a form of tempo characters or indices 2 wherein the particular group that will be used throughout the piece is shown in the index 3. It will be noted that these figures run from 0 to 90 in a progression of tens, and characters there- 90 in represent either retardation or acceleration graduated proportionally to their magnitude, or to their location in the sequence in which they commonly occur by moving the dial to cause the like character thereon 95 to register with the gage line 17 on the tracker bar 14. The character 50, as at 4, is indicative of the controlling tempo as has been heretofore used.

In Fig. 2 the index 5 shows the group of 105 figures running from 0 to 10 successively. The tempo indices 6 vary according to the tempo requirements of the piece.

In Fig. 3 the index 7 and the tempo indices 8 are composed of letters running from 110 0 and thence in alphabetical progression, and each of said letters are intended to sig-

nify the amount of relative tempo variation, which variation is fixed for each letter and in accord with its alphabetic position in the said progression.

5 In Fig. 4 another form of tempo indices is shown, as at 10, wherein the said indices are similar to those indicated in Fig. 1, with the addition of an exponent in the form of a letter which may be placed before or behind said tempo indices. In the present form it will be noted that the exponent letters consist of merely three characters, being those of the well known type as at present used in such markings, namely A 10 for accelerate, R for retard, and T for tempo. It will be noted that in this group of tempo characters, for instance at 11 and 12, the characters A and R are applied to two like numbers, 90, and at various points 15 in the row or series of characters A is placed before like or unlike numbers. As before indicated A stands for accelerating or accelerando, and used as such in the present standard markings stands for the 20 general term only, whereas in my present improvement the acceleration is indicated in terms, in other words the letter A might have the numerals 50, 60, or 10, as the exponent of the amount or degree of acceleration 25 would be, thereby precisely indicated; and where it occurs without a numeral, it indicates acceleration graduated between that indicated by the adjacent indices. The same may be said of the letter R. T, however, indicating the return to the strict tempo controlling the piece and generally indicated, as at 13, Fig. 4, may or may not have an exponent, for if at the beginning 30 of the piece T stands for a value of 60, wherever T occurred thereafter would naturally indicate the original tempo of 60, and would not thereafter require any further indication as either the letter or the 35 number could be used separately and its meaning understood.

In Fig. 5 I have shown a fragmentary portion of the music roll 1 in position on a tracker-bar 14, showing a series of the indices 15 after the manner of my present improvement. It will be noted throughout the drawings that short horizontal lines, as 16, Fig. 5, are placed either under or opposite to the said indices, these lines running from the indices to the edge of the music roll for

the purpose of having a precise point at 55 which to limit one degree of time and to change to the next succeeding one, and which, during the movement of the said roll registers with a line which may be placed on the tracker-bar, as at 17. 60

The indicator shown in conjunction herewith may be mounted on two leaves 18 and 19 which have at their opposite ends elongated slots 20 and 21; said slots being engaged on pivots 22 and 23. The rod 24 in 65 suitable engagement with manually controlled means, not shown, is moved up or down in a vertical direction thus causing the dial 25 to also move up and down in a vertical direction. It will be noted that 70 the dial has a series of numbers similar to those used as indices on the music roll and having lines 26 to one side thereof and, as in the case of the music roll, running from the edge of the dial to the number. It is 75 obvious that upon shifting this dial until the corresponding number comes opposite the mark 17 on the tracker-bar 14 that the player control operating in conjunction with the said dial will thereupon be controlled 80 accordingly.

Having thus described my invention, I claim:

In perforated music sheets for player pianos provided with a gage mark on the 85 tracker bar and with settable tempo-, and expression-graduation mechanism and a graduated scale whose graduations are marked with characters of a sequence in common use, whereby such mechanism may 90 be properly set at such gage mark, the combination, on a margin of such sheets of a tempo and expression scale, and the graduations thereof, with printed characters of the same sequence as used on the mechanism 95 scale, the marks and numbers of said sheet-scale adapted during the use of such sheets in the player, to register successively with said gage-mark and to thereby indicate to the performer the instant, and the speed at 100 which to move such mechanism and the scale thereof, to register with the gage mark the same character of the mechanism-scale as registers therewith on the sheet-scale.

CHARLES SCHULTZ JASSEY.
